UNITED STATES PATENT OFFICE.

CHARLES EDWIN HAMILTON, OF LOS ANGELES, CALIFORNIA.

IRONING PAD.

Application filed May 14, 1926. Serial No. 109,019.

The invention relates to spring ironing pads as employed in ironing tables for pressing or in rolls of ironing machines, for example, pads of the type consisting substantially of a base plate upon which are secured a plurality of adjacent and helically coiled springs, the latter being covered by suitable caps or the like which support a fabric top composed of one or more layers of suitable padding material. In a prior application for U. S. Letters Patent filed by me the last day of May, 1923, Serial No. 635,853, I have disclosed a substitute for a large portion of the fabric padding generally employed, in that there is interposed between the spring caps or springs themselves individual blocks of more or less resilient material of a heat insulating nature. The arrangement set forth therein involves the use of a metallic cap fitting over the outer or free end of a spring to cover the same and a second metal cap secured to or formed integrally with the first named cap for retaining and supporting the block of heat insulation material fitted snugly therein.

I have found it possible, however, with respect to the insulating material substituted to eliminate this double cap and receptacle member while retaining the advantages of the intermediate resilient blocks of heat insulation material; and the present invention has for its object a capping member for the free end of the spring, and, also, to dispense entirely with the use of cap members of the aforesaid character and to employ merely a disk which is suitably formed to admit of its being removably secured to a spring end. When intended for use with insulation material, the coil disk is provided, also, with means for attaching and holding thereto a block of the heat insulating material in manner such as to be insured against dislodgment. A further object of the invention resides in a construction of capping member which is of itself not only more readily and inexpensively manufactured, but in its use generally facilitates the assembly of the pad. A still further object resides in the novel arrangement as applied to rolls, whereby through the use of the novel disk members it becomes possible to hold in position and prevent from slipping the covering material or first layer of the padding for the blocks.

To this end, the invention comprises a novel disk member provided with integral

and resilient means of attachment to the spring ends and from which may be struck up suitable holding portions for attaching to said disk a block of heat insulating material or for holding the covering material against slipping, or both.

The nature of the invention, however, will best be understood when described in connection with the accompanying drawings, in which:

Figure 1 is a fragmentary detail view, partly in section, illustrating a plurality of springs and the novel means for supporting the fabric padding or covering of an ironing pad with intermediate heat insulating material.

Figure 2 is a similar view illustrating a modification.

Figure 3 is a perspective view of the novel disk member as constructed for retaining a block of heat insulation material.

Figure 4 is a vertical section of a disk with block of insulation material held thereby.

Figure 5 is a fragmentary plan view of a portion of an ironing roll with a section of the fabric covering removed and showing also the novel manner of holding in position, and preventing from slipping, the covering material.

Figure 6 is an enlarged fragmentary transverse section through the pad shown in Figure 5.

Figure 7 is a fragmentary section of a simplified form of the pad supporting or capping member for the spring ends, and

Figure 8 is a plan view of the modified member.

Referring to the drawings, the ironing pad may be of various shapes to suit, for example ironing machines of the roll type, Figures 5 and 6, and embodies a base plate 10 upon which is mounted a plurality of adjacently disposed resilient members as the coil springs 11 with convolutions reduced in diameter at both ends, Figure 1, or only at the base end, Figure 2. These resilient members may be secured in any suitable manner to the base plate; and at their tops receive the novel disk member 12, more particularly shown in Figures 3, 4, 7 and 8 of the drawings. These disk members 12, in accordance with the invention, are so constructed as to be readily attachable to and removable from the tops of the respective springs 11; and, for example, two forms of

the disk member may be employed to accommodate and provide for adequate attachment to the two types of springs, namely, the conical free ended spring, Figure 1, and the full diameter end, Figure 2, of the drawings.

To this end, the novel capping member is constructed as shown of a circular disk of metal 12 which, when intended for use with heat insulation material, may be stamped out with a plurality of fins or projections 13 extending from its circumference, or edge in the case of a rectangular or other straight sided type, which rim portions are then turned upwardly at the edge of the disk to form a shallow dish-like member to receive and secure a block of heat insulation material 14 against becoming dislodged laterally. The blocks 14 may be of cork, leather, asbestos or composition of a more or less resilient and heat resisting nature, and are designed to be further held in position by spurs 15, preferably two, and which are struck upwardly from the disk. These spurs are pointed at their free ends to allow ready insertion of a block thereover, and will serve to further hold said block sufficiently to prevent its dislodgment. In the use of two or more of the spurs located eccentrically, rotational movement of a block is provided against; and in the manufacture of the disk, the said spurs 15 may be barbed, as indicated, to insure against too ready withdrawal of a block from a disk.

Also, in forming up the sides or holding flanges 13 of a disk, the intermediate portions left thereby are designed to be turned downwardly and under the disk with a more or less doubling of a portion thereof upon itself. This forms a plurality of curved spring fingers 16 adapted to fit within a free spring end to receive the same and be held under a slight spring pressure to the uppermost convolution of said end of a spring. In the event that full diameter free end springs are employed, as indicated in Figure 2 of the drawings, the rim portions left after striking up the projections 11 are not turned under to the extent required in the case of the tapered-off spring ends, but are spread sufficiently to fit over the outside of the convolutions, as shown in Figure 2, rather than within the convolutions as in the embodiment illustrated in Figure 1.

The particular construction set forth lends itself also to the prevention of slipping of a superposed covering strip of padding 20, Figures 5 and 6, in that certain of the spurs 15, for example those of a number of rows along the entire length of the roll near the edge of the material, may be of length sufficient to project a slight distance above the tops of the correspond-

ing blocks 14 and pierce the material 20. If this end of the covering material should then eventually wear sufficiently to no longer be properly held thereby, it would be necessary merely to cut off a short length 70 and then replace the strip over the protruding spurs. By the foregoing expedient, longer life of the padding material is insured and all danger of slipping and bunching thereof obviated. 75

When it is not desired to utilize an intermediate layer of heat insulating material, the simplified form of capping disk, illustrated in Figures 7 and 8, may be employed. As shown, only the downwardly-turned 80 spring fingers 16 are then provided integral with the body of the disk as the upper projections or flange members 13 are not required. The upstanding spurs 15, however, may be retained for holding of the 85 padding material, but will be somewhat shorter; and it is preferred, furthermore, to provide the disk with perforations 21 for draining the pad of moisture. 90

I claim:

1. In an ironing pad of the character set forth: a capping disk member for the free end of a conical spring, comprising a flat metal disk having integral resilient fingers downwardly directed from the edge thereof 95 to afford spring holding means for removably attaching the disk to the spring end.

2. In an ironing pad of the character set forth: a capping disk member for the free end of a conical spring, comprising a flat 100 metal disk having integral resilient fingers doubled upon themselves to afford spring holding means for removably attaching the disk to the spring end.

3. In an ironing pad of the character set 105 forth: a capping disk member for the free end of a conical spring, comprising a flat metal disk having integral resilient fingers downwardly directed from the edge thereof to afford spring holding means for removably attaching the disk to the spring end, and said disk being provided also with upstanding holding spurs. 110

4. In an ironing pad of the character set 115 forth: a capping disk member for the free end of a conical spring, comprising a flat perforated metal disk having integral resilient fingers downwardly directed from the edge thereof to afford spring holding means for removably attaching the disk to the spring end, said disk being provided also with upstanding holding spurs. 120

5. The combination with the padding material of an ironing pad; of a resilient supporting structure therefor, comprising a base plate, a plurality of adjacently disposed helical spring members carried thereby with the outer end free, and disk members having means for attachment of a disk to the free end of the springs and provided with 130

upstanding holding spurs adapted to pierce the padding material and hold same against displacement relatively the said resilient supporting structure.

- 5 6. In an ironing pad of the character set forth: disk members fitted to the free end of the respective springs, comprising a flat metal disk having integral resilient fingers downwardly directed from the edge thereof
10 for removably attaching the disk to the spring, and having holding portions upturned from its edge.

7. In an ironing pad of the character set forth: disk members fitted to the free end 15 of the respective springs, comprising a flat metal disk having integral resilient fingers downwardly directed from the edge thereof for removably attaching the disk to the spring, having holding portions upturned
20 from its edge, and upstanding holding spurs extending from the body of the disk.

8. In an ironing pad of the character set forth: disk members fitted to the free end 25 of the respective springs, comprising a flat metal disk having integral resilient fingers downwardly directed from the edge thereof for removably attaching the disk to the spring, having holding portions upturned from its edge, and upstanding barbed holding spurs extending from the body of the disk.

9. A resilient supporting structure for 30 ironing pads, comprising a base plate, a plurality of adjacently disposed helical spring members carried thereby, disk members fitted to the free end of the respective springs, blocks of heat insulating material carried by the respective disks, a said disk having portions upturned from its edge to hold a block against lateral displacement and having also spurs struck upwardly eccentrically from the body of the disk and over which a block is secured, and said disk having means integral therewith for removably holding a disk to the outer convolution 35 of a corresponding spring.

10. A resilient supporting structure for ironing pads, comprising a base plate, a plurality of adjacently disposed helical spring

members carried thereby, disk members 50 fitted to the free end of the respective springs, blocks of heat insulating material carried by the respective disks, a said disk having portions upturned from its edge to hold a block against lateral displacement 55 and also having spurs struck upwardly eccentrically from the body of the disk and over which a block is secured, and resilient fingers turned downwardly from the edge of a disk adapted to engage with the outer 60 convolution of a corresponding spring.

11. The combination with the padding material of an ironing pad; of a resilient supporting structure therefor, comprising a base plate, a plurality of adjacently disposed 65 helical spring members carried thereby, with outer end free, disk members fitted to the free end of the respective springs, blocks of heat insulating material carried by the disks, and means projecting upwardly from the 70 disk members and through the heat insulating blocks to pierce the padding material to hold the same against displacement relatively to the said resilient supporting structure. 75

12. The combination with a padding material of an ironing pad; of a resilient supporting structure therefor, comprising a base plate, a plurality of adjacently disposed helical spring members carried thereby, with 80 outer ends free, disk members fitted to the free end of the respective springs, blocks of heat insulating material carried by the disks, a said disk having portions upturned from its edge to hold a block against lateral displacement and having also spurs struck upwardly eccentrically from the body of the disk to receive a block, a number of the spurs being of a length to project beyond the tops of the respective blocks and pierce 85 the padding material to hold the same against displacement relatively to the said resilient supporting structure, and said disk having means integral therewith for removably holding a disk to the outer convolution 90 of a corresponding spring. 95

In testimony whereof I affix my signature.
C. EDWIN HAMILTON.
